COMBUSTION CONTROL

John L. Harris, Minneapolis, Minn., assignor to
Minneapolis-Honeywell Regulator Company,
Minneapolis, Minn., a corporation of Delaware

Application December 23, 1939, Serial No. 310,687

11 Claims. (Cl. 236—21)

This invention relates to automatic burner controls and more particularly to automatic controls for gas or oil fired steam boilers.

It is an object of this invention to provide a simple burner control system which modulates the flow of fuel to a burner in accordance with the actual demand, which prevents the flow of fuel to the burner from being reduced below that necessary to provide proper burner operation, which intermittently places the burner into and out of operation when the minimum operating rate of the burner is greater than the actual demand, and which places the burner out of operation regardless of the demand for burner operation whenever unsafe operating conditions occur.

More specifically, it is an object of this invention to provide a pressure actuated burner control system of the type employing a pressure motor for regulating fuel flow with a simple and positive arrangement for regulating the flow of fuel to the burner and discontinuing operation of the burner upon the occurrence of improper operating conditions.

Other objects of the invention will appear from the following description and the appended claims.

For a full disclosure of this invention reference is made to the following description and to the accompanying drawings, in which

Figure 1 illustrates diagrammatically a boiler control system embodying the features of this invention,

Figure 2 is an elevation partly in section of the fuel valve employed in Figure 1,

Figure 3 is a sectional elevation of the fuel valve controller,

Figure 4 is a sectional view taken on line 4—4 of Figure 3,

Figure 5 is an elevation partly in section of a modified valve controller,

Figure 6 is a diagrammatic illustration of a modified boiler control system, and

Figure 7 is a detail view of the valve controller employed in the system of Figure 6.

Referring to Figure 1, reference character 1 indicates a boiler having a combustion chamber 2 in which is located a gas burner 3 which is supplied with gas through a pipe 4 leading from a main fuel valve generally indicated as 5, this valve being connected with a gas main 6. The burner 3 is provided with a pilot burner 7 which is connected to the gas main 6 by pipe 8 having a control valve 9 interposed therein. The boiler 1 is provided with the usual steam off-take pipe

10 and a flue 11 having an uptake damper 12 therein. This damper is operated by a chain 13 running over pulley 14 and connecting to a lever 15 attached to the main fuel valve 5. The boiler 1 is also provided with a low water cut-off 16 and with a safety pilot control 17. The low water cut-off 16 includes a float operated switch (not shown) which is opened whenever the water level in the boiler falls too low. The safety pilot control 17 consists of a switch which is opened by a thermostat responding to the pilot flame temperature, this switch opening whenever the pilot becomes extinguished.

Referring to Figure 2, the main fuel valve 5 consists of a valve body 20 having an inlet chamber 21 and an outlet chamber 22 separated by a partition 23 having a valve port 24 located therein. This valve is provided with the usual valve bonnet 25 having mounted thereon the packing gland 26 for the valve stem 27, this valve stem 27 carrying a valve member 28 located below the valve port 24. The bonnet 25 is also formed to support a diaphragm cage 29 in which is mounted the diaphragm 30. This diaphragm 30 preferably consists of a number of superposed and communicating metallic cells 31, the topmost cell 31 engaging the cover plate 32 for the diaphragm cage. Abutting the lower surface of the lower diaphragm 31 is a pressure plate 33 which engages the head 34 of the valve stem 27. A spring 35 rests on the packing gland nut and engages a cup member 36 which in turn abuts the valve stem head 34. It will be apparent that by this arrangement the spring 35 serves to force the valve stem 27 upwardly thereby normally collapsing the diaphragm 30 and forcing the valve member 28 against its seat. It will also be apparent that when pressure is applied to the diaphragm 30, it will expand against the action of spring 35 for moving the valve stem 27 downwardly for thereby forcing the valve member 28 from its seat. The lever 15 for operating the uptake damper 12 is pivoted to a shaft 40 which may extend from side to side of the diaphragm cage. This lever is formed with a curved portion surrounding the cup member 36 and is provided with a pin 42 engaging a slot 41 formed in the cup member 36. By this arrangement downward motion of the cup member 36 will cause downward rocking of the lever 15 about its pivot 40. This in turn will cause opening of the uptake damper 12. Thus upon application of pressure to the diaphragm 31 the main gas valve to the burner is opened and the uptake damper 12 is opened simultaneously therewith.

Mounted upon the diaphragm cage 29 is the valve controller generally indicated as 45. Also mounted upon the diaphragm cage is a filter 46 (Figure 1) the inlet of which is connected with a pipe 47 leading from the steam off-take pipe 10. The outlet of this filter is connected by a pipe 48 to the inlet of the controller 45. The outlet of the controller 45 is connected by a pipe 49 (Figure 2) which is formed partly coil shaped and which is connected to the diaphragm 30. The filter 46 is also provided with the usual blow down connection 50 having a blow down valve 51 located therein.

Referring now to Figure 3 the construction of the valve controller will be described. This valve controller consists of a casing 53 housing a pilot valve mechanism generally indicated as 54. This pilot valve mechanism includes a valve casing 55 which is secured to a restrictor member 56. This restrictor member is shown in detail in Figure 4 and is provided with an inlet passage 57 to which is connected the steam line 48 of Figure 1 which leads from the filter 46. The restrictor member 57 is provided with a restriction 58 which cooperates with a needle valve member 59 in controlling the flow of steam from the inlet passage 57 into an outlet passage 60. This outlet passage 60 is connected to the pipe 49 which leads to the diaphragm 30 of the main valve 5. It will be apparent that by adjusting the needle valve 59, the rate of flow of filtered steam from the boiler into the outlet passage 60 may be varied as desired. The outlet passage 60 is provided with a downwardly extending passage 61 which coincides with a passage formed in the valve casing 55 and communicates with a bleed port member 62 which extends downwardly into the chamber 63 in the valve casing 55. The valve casing 55 is provided with a threaded opening in its bottom wall for receiving a pilot valve guide member or plug 64 which is bored out to provide a guide for the pilot valve plunger 65, this plunger being secured to a sleeve member 66 carrying a crater shaped valve disc 67 cooperating with the bleed port member 62 in controlling the bleed of steam from the outlet passage 60 of the restrictor member. It will be apparent that movement of the valve plunger 65 will vary the pressure maintained in the outlet passage 60 and in the diaphragm 30 of main valve 5. Thus upon upward movement of the valve stem 65 the valve disc 67 will be shifted closer to the bleed port 62 thereby decreasing the flow of steam from the outlet passage 60 which will cause the pressure in this passage and in the diaphragm 30 to increase which will cause expansion of this diaphragm against the action of the spring 35 from opening the fuel valve and uptake damper. The valve casing 55 is connected to a drain pipe 10 which conveys steam and condensate issuing from the bleed port 62 to a suitable drain. In order to prevent steam or condensate from escaping from the valve casing 55, the guide member 64 is provided with a stuffing box 71 which prevents escape of steam or condensate around the valve plunger 65.

The valve plunger 65 is raised and lowered by means of a floating lever 72. The right hand end of this lever 72 is carried by a knife edge 73 formed on a link 74 which in turn is pivoted at 75 to the clapper or armature 76 of an electromagnetic actuating device 77 such as employed in the well known clapper type electric relay. The electromagnetic device includes a stationary

5 electromagnetic coil which attracts the clapper or armature 76 which is pivoted at the rear as appears in Figure 3. When the coil or electromagnet is energized the clapper 76 is pulled upwardly which thereby causes the link 74 to be likewise pulled upwardly to a fixed position. However, when the electromagnet is deenergized, the clapper 76 will drop thereby causing the link 74 to be lowered. The left hand end of the floating lever 72 is carried normally by an adjusting screw 80 mounted on lever 81, this lever being pivoted at 82 and being actuated by a plunger 83 which is actuated by a bellows 84. This bellows 84 is surrounded by a cup 85 which is connected by a pipe 86 to the blow down pipe 50 leading from the filter 46. Bellows 84 is therefore subjected to the steam pressure in the boiler. This bellows is biased by means of a spring 81 which urges the lever 81 in the clockwise direction about pivot 82. The spring 81 may be varied in tension by means of an adjusting nut 88 carried by a stationary screw 89. This adjusting nut may also carry an indicator 90 which extends through a slot 91 in casing 53 thereby indicating the pressure for which the instrument is adjusted.

20 Reference character 95 indicates a follow-up lever which is pivoted to a shaft 96 carried by ears 97 formed in the back of the casing 53, this follow-up lever extending through a slot 98 in the back of the casing and rearwardly to a point beneath the diaphragm 30 (Figure 2). This lever 95 is provided with a slot 99 for receiving a threaded actuating member or screw 100 which abuts the pressure plate 33. The end of the 30 follow-up lever 95 which extends within the casing 53 is attached to a follow-up spring 102 which in turn is attached to the lever 81 immediately above the plunger 65. This follow-up spring 102 thus serves to urge the lever 95 in a clockwise direction as viewed in Figure 2 thereby maintaining the screw 100 in engagement with the pressure plate 33. It will be apparent that upon downward movement of the pressure plate 33 the lever 95 will be rotated counter-clockwise 40 thereby increasing the tension on spring 102 and that upon upward movement of the pressure plate 33 the lever 95 will be rotated in the opposite direction for decreasing the tension on spring 102.

45 It will be apparent that the position assumed by the lever 81 is dependent upon three forces, namely, a counterclockwise force produced by the pressure on bellows 84, a clockwise force produced by the biasing spring 87 and a counterclockwise force produced by the tension follow-up spring 102. Under normal operating conditions as will be presently described more in detail, the electromagnetic device 77 will be energized which causes the right hand end of the 50 floating lever 72 to be stationarily pivoted in normal position as shown in Figure 3. Upon a decrease in boiler pressure, the force produced by bellows 84 will decrease thereby causing the lever 81 to be rocked clockwise by the biasing spring 87. This will cause the left hand end of the floating lever 72 to be raised which will in turn raise the valve plunger 65. This will cause the valve disc 67 to approach the bleed port 62 for reducing the rate of bleed of steam from this 55 port thereby increasing the pressure applied to the diaphragm 30. This increase in pressure will cause diaphragm 30 to expand thereby driving the valve stem 27 downwardly against the action of spring 35 for opening the gas valve wider and simultaneously rocking lever 15 for opening the

uptake damper 12 a corresponding amount. This downward movement of the diaphragm 30 will also cause counter-clockwise rotation (as viewed in Figure 2) of the lever 85 about its pivot thereby increasing the tension on the follow-up spring 102. This increase in tension on the spring 102 will serve to cause the left hand end of lever 81 to be lowered as the main valve opens thereby lowering the pilot valve plunger 65 and increasing the rate of bleed from the passage 61 which lowers the pressure applied to the diaphragm 30. In other words, as the diaphragm 30 expands due to the increase in pressure applied to it, the pilot valve is repositioned by the follow-up spring for lowering the pressure applied to the diaphragm. By this arrangement a point is reached wherein the pressure applied to the diaphragm is just sufficient to maintain it stationary against the action of biasing spring 35. Stated another way, upon a decrease in boiler pressure, the valve plunger 65 will be initially shifted considerably farther than necessary in order to cause the main valve to assume the desired position. Then as the main valve approaches the desired position the pilot valve is forced back by the increase in tension on the follow-up spring so that when the main valve reaches the desired position, the pilot valve is positioned for just maintaining the main valve stationary. This arrangement in which the pilot valve is initially positioned farther than necessary and returned to the proper position, provides a positive driving force for causing the valve to assume the proper position in spite of friction either in the valve packing gland or in the uptake damper operating mechanism. Upon an increase in pressure in the boiler the opposite action will occur, namely, the lever 81 will be rotated counter-clockwise for lowering the end of lever 72 and thus lowering the valve plunger 65 which increases the rate of bleed through port 62. This decreases the pressure applied to the diaphragm which permits the spring 35 to cause upward movement of the valve stem for closing the valve and uptake damper. This upward movement permits clockwise rotation of the follow-up lever 95 which decreases the tension on the follow-up spring 102, this in turn causing clockwise movement of lever 81 for raising the valve plunger 65. Thus when the main valve reaches the proper position for the existing boiler pressure, the valve plunger 65 is positioned for maintaining the main valve in this correct position. With this positive follow-up arrangement it will be apparent that the valve plunger 65 will be positioned for applying as necessary either maximum pressure or zero pressure to the diaphragm 30 for causing it to move to the position demanded by the bellows 84. It should be noted that in the event of failure of the follow-up spring 102 the system will still continue to function and the only result of such breakage will be a hunting action of the valve due to the fact that the valve plunger 65 is moved more than necessary by the bellows 84.

In the control of a gas burner it is essential that the flow of gas to the burner must not be reduced below an amount necessary to maintain the burner in proper operation. In order to prevent the control system just described from reducing the flow of gas to the burner below the minimum allowed amount, provision is made for taking control of the valve plunger 65 away from the bellows 84 whenever this bellows attempts to close the valve beyond a predetermined minimum position. This minimum posi-

tion arrangement includes a lever 110 carrying an adjustment screw 111 and being pivoted to a knife edge member 112. The lever 110 is also attached to a minimum position follow-up spring 113 which is in turn attached to a horizontal extension 114 of the follow-up lever 95. The lever 110 is also attached to a minimum position adjusting spring 115 which is attached to an adjusting screw 116 mounted upon a bracket 117. 5 It will be apparent that as the diaphragm 30 expands for opening the gas valve, the follow-up lever 95 will be rotated for increasing the tension of spring 113. The tension on spring 113 is therefore dependent upon the valve position. 10 The adjusting spring 115 due to its being connected to the lever 110 on the opposite side of the knife edge member 112 from the spring 113 acts as a balancer for spring 113. When the main valve is opened beyond the desired minimum position as determined by the tension of spring 115 the tension of spring 113 will overcome spring 115 for rocking the lever 110 counter-clockwise thus causing the screw 111 to be entirely disengaged from the floating lever 72. 15 However, as the main valve closes, the tension on spring 113 will be reduced which will permit the spring 115 to rotate lever 110 clockwise for causing the adjusting screw 111 to engage lever 72 at the time that the main valve assumes its minimum position. Now the valve plunger 65 will be held up by the lever 110 independently of the lever 81. Consequently the lever 81 is incapable of causing the main valve to be closed beyond the predetermined minimum position. By 20 adjusting the tension of spring 115 the minimum position may be readily adjusted as desired. Thus by increasing the tension on spring 115 the main valve must be open a greater extent before the spring 113 overcomes the tension of spring 115 and thus the valve is opened wider at its minimum position. Conversely as the tension on spring 115 is decreased the valve is permitted to close a greater extent. 25 The energization of the electromagnetic device 77 is controlled by the low water cut-off 16, the safety pilot control 17, and also by a mercury switch 120 which is located within the casing 53. This mercury switch is mounted upon a pivoted switch carrier 121 having a slot 122 therein 30 which receives a pin 123, this pin being carried by a lever 124 attached to the lever 81. The mercury switch 120 is therefore actuated by the bellows 84 which responds to boiler pressure. Upon an increase in boiler pressure the lever 81 and 35 its extension 124 are rotated counter-clockwise which causes rotation of the mercury switch 120 clockwise to open position. The parts are so proportioned and adjusted that the mercury switch 120 remains closed (as shown) when the boiler pressure is within the normal operating range of the pilot valve. However, when the boiler pressure rises slightly above this normal operating range, the mercury switch 120 is opened. 40 45 Referring again to Figure 1, reference character 126 indicates a step-down transformer one terminal of which is connected by wire 127 to the low water cut-off 16. This low water cut-off is in turn connected by wire 128 to the safety pilot control 17 which is in turn connected by wire 129 leading to the electromagnetic device 77 of the valve controller. This device is in turn connected by wire 130 (Figure 3) to the mercury switch 120, the other terminal being connected by a wire 131 to a pressure responsive device 132, this 50 55 60 65 70 75

in turn being connected by wire 133 to the transformer 126. The pressure controller 132 is connected by pipe 134 to the pipe 49 which leads from the outlet passage 60 of the restrictor device 56 to the diaphragm 30 of the main valve. This controller 132 therefore responds directly to the steam pressure in the diaphragm 30. Its function is to open its switch whenever the pressure in diaphragm 30 rises to the maximum pressure which the diaphragm 30 may safely be subjected to.

Due to the series circuit arrangement between the low water cut-off, the safety pilot control, the controller 132, and the mercury switch 120, all of the switches must be closed in order to energize the electromagnetic device 71. In the event that either the boiler water level falls to an unsafe value, the burner pilot becomes extinguished, or the boiler pressure rises too high, the energizing circuit for the electromagnetic device 71 will be broken which will cause the clapper or armature 76 to drop about its pivot for lowering the position of knife edge 73. This will lower the valve plunger 65 for increasing the rate of bleed through port 62 to a maximum which causes the main valve to close entirely. At this time a stop screw 135 which is carried by a bracket 136 prevents either the lever 81 or the lever 110 from raising the left hand end of lever 72 sufficiently to cause sufficient upward movement of valve 64 as would cause the main valve to open. This stop screw 135 has the additional function of preventing upward movement of the valve plunger 65 to an extent which would cause the pressure applied to the diaphragm 30 to be excessive. In other words, this stop screw 135 when properly adjusted determines the maximum pressure which can be applied to the diaphragm 30 and in addition prevents the levers 81 and 110 from causing opening of the main valve when the electromagnetic device 71 is deenergized.

In the event that the pressure applied to the diaphragm 30 becomes excessive due to either improper adjustment of the stop screw 135 or improper adjustment of the needle valve member 59, the pressure responsive device 132 will deenergize the device 71 for causing the valve plunger 65 to drop to its lowermost position for reducing the pressure applied to diaphragm 30.

In some cases it may be desirable to provide for positively closing the main valve in the event that the pilot valve 62-67 fails to function properly. To obtain this result, the outlet passage 60 of the restrictor member 56 may be provided with a valve port 140 which is covered by a valve member 141 held normally closed by means of a spring 142. This valve member is provided with a plunger 143 coinciding with plunger 144 carried by a sleeve member 145, a spring 146 surrounding these plungers. The sleeve member 145 is carried by the valve plunger 147 extending through a guide member 148 which is exactly the same as the guide member 64. This plunger 147 is adapted to be actuated by a lever 149 which is pivoted at 150 and which is engaged by a knife edge member 151 carried by the plunger 83. Under normal conditions the lever 149 will not engage the plunger 147 and therefore the valve member 141 will normally remain against its seat. However if boiler pressure rises above the setting of the control, the lever 149 will engage plunger 147 forcing it upwardly. This will cause the plunger 146 to engage plunger 143 for forcing the valve member 141 away from its seat against the

pressure of the steam in the chamber 60. The spring 146 will then serve to snap the valve 140 wide open for thereby reducing the pressure in outlet passage 60 and the diaphragm 30 to zero which will permit the main valve to close entirely. It will be noted that the safety pilot valve 141 has the same function as the mercury switch 120, namely, causing complete closing of the main valve when boiler pressure rises above the setting of the control. Unless the added safety afforded by utilizing both arrangements is desired, either the mercury switch or the safety pilot valve may be omitted.

It will be noted that steam pressure in the boiler is required in order to render automatic control of the valve possible. In order to start up a cold boiler it is necessary to manually open the valve. This is done simply by pressing down on the lever 15 which both opens the gas valve and the uptake damper. The lever 15 is then held in depressed position by means of a stop 154 which is pivoted to the diaphragm cage 29 by screw 155, this screw being located above and to one side of the lever 15. This stop 154 is preferably arranged so that it will hold the lever 15 depressed sufficiently to maintain the valve in approximately half open position. This will prevent maximum firing of the boiler when it is cold and thus avoid any damage to the boiler and brick work due to sudden heating. When the boiler begins to steam, steam will flow through the pipe 47, filter 46, and pipe 48 to the inlet of the restrictor member 56 past the restriction and through tube 49 into the diaphragm 30. At this time the boiler pressure will be below the setting of the control which will cause the lever 72 to be forced upwardly against the stop screw 135 by lever 81 which will position valve plunger 65 to reduce the bleed to a minimum. Thus as the boiler pressure rises initially, the steam pressure will cause the diaphragm 30 to expand thereby opening the gas valve and uptake damper wide. The stop 154, due to its being pivoted to one side of the lever 15 will now fall away from the lever 15 thereby returning the system to complete automatic control. The valve and uptake damper will remain wide open until the boiler pressure rises to within the control range of the controller at which time the pressure on bellows 84 will be sufficient to overcome the biasing spring 87 for lowering the valve plunger 65 which causes the main valve and damper to recede from their wide open positions an amount sufficient to maintain the boiler pressure constant. The control will now function in the manner described in detail above for maintaining the desired boiler pressure. Thus the control will serve to positively position the valve and uptake damper between their minimum and wide open positions in accordance with the load on the boiler. However, at no time will the lever 81 close the valve and damper beyond their minimum positions due to the action of the minimum position arrangement described. In the event that the load on the boiler is so low that operation of the burner at its minimum rate produces more steam than necessary, the boiler pressure will rise to a point wherein the mercury switch 120 opens for deenergizing the electromagnetic device 71 which will cause complete closure of the valve and uptake damper. At such times the valve and damper will be alternately closed and opened to their minimum positions for maintaining the proper boiler pressure.

Referring to Figure 5, this figure shows a

modified form of controller for controlling the main valve. In this modification the electromagnetic device instead of positioning the valve plunger as in Figure 3, positions a vent valve which is capable of venting the motor diaphragm independently of the pilot valve. In this figure the restrictor and pilot valve mechanism are contained in a single housing 160. This housing 160 is provided with a connection for the pipe 48 leading from the filter and opening into a passage 161 in which the needle valve screw 162 is located. The steam after flowing past the restriction enters an outlet passage 163 communicating with the motor diaphragm through pipe 49. The passage 163 also communicates through a valve port member 164 with a valve chamber 165 containing pilot valve mechanism which is substantially the same as shown in Figure 3. If desired a spring 166 may be employed for forcing the pilot valve and plunger 65' downwardly. This plunger 65' is operated by a pivoted lever 167, the pivot for this lever being fixed instead of being movable as the corresponding lever of Figure 3. This lever 167 is actuated by the levers 81' and 110' corresponding to the levers 81 and 110 of Figure 3. The operating mechanism for these levers is the same as in Figure 3 and accordingly this mechanism is not redescribed at this point.

The chamber 163 also communicates with a relief valve passage 169 which communicates with a valve port covered by a valve member 170. This valve member is urged upwardly by means of a spring 171 and is provided with a valve stem 172 extending upwardly through a plug 173. The valve stem 172 is attached to a member 174 having a slot 175 for receiving the lever 176 which is attached to the clapper or armature 177 of the electromagnetic device 178. When this electromagnetic device 178 is energized, the clapper 177 is pulled upwardly as shown which causes the lever 176 to force the valve stem 172 downwardly thereby forcing the valve member 170 against its seat. At this time the control will function in the same manner as the device of Figure 3, that is, the pilot valve will control the pressure applied to the valve diaphragm for positioning the valve and damper in accordance with boiler pressure, and providing also for preventing the valve from being closed beyond the minimum position. The electromagnetic device 178 is controlled by exactly the same controls as shown in Figure 1 including the mercury switch 120'. Whenever the electromagnetic device 178 is deenergized the weighted clapper or armature 177 will drop downwardly thus causing the lever 176 to engage the top of slot 175 with a hammer action for disengaging valve member 170 from its seat. This action will also be supplemented by the spring 171 and also by the pressure under valve 170 to thereby insure that the valve 170 will disengage its seat even though it may tend to stick. This will exhaust all pressure from the motor diaphragm for thereby causing the gas valve and damper to close completely. It will be noted that by the arrangement of the valve port and valve member disclosed water cannot accumulate adjacent the valve seat and consequently no scale deposit will occur which would cause sticking of the valve member 170 to its seat.

In Figures 6 and 7 is shown a control arrangement in which the gas valve is positioned in accordance with the pressure at the outlet of the valve instead of in accordance with valve position. This arrangement has the added advantage of dispensing with the necessity of a pressure

regulating valve ahead of the throttling valve, as required with a valve position type control as in Figure 1. In Figure 6 the gas valve 180 is provided with a vertical frame 181 which supports a pressure motor 182. This pressure motor may consist of a casing 183 covered by a flexible diaphragm 184 which is connected by a rod 185 to the junction of a pair of toggle members 186 and 187. The toggle member 187 is pivotally connected to the valve stem 188 while the toggle member 186 is pivoted to the frame 181. This toggle member 186 is formed as a bell crank carrying a weight 189 for biasing the pressure motor 182. This weight serves to collapse the toggle formed by the members which causes the valve stem 188 to be forced downwardly for forcing the valve member against its seat. Upon increase in pressure on the diaphragm 184 this diaphragm will move to the left which will cause upward movement of the valve stem 188 for opening the main valve. This valve stem 188 is also attached to a lever 190 which is pivoted so as to rotate in a counter-clockwise direction upon opening of the main valve. This lever 190 operates the uptake damper 12. The pressure motor 182 is connected by a pipe 191 to a float chamber 192 containing a float valve 193. This float chamber is in turn connected by a pipe 194 to the pilot valve 195 of the valve controller generally indicated as 196 (Figure 7).

The pilot valve mechanism per se 195 may be the same as shown in Figures 3 and 5 and includes a pilot valve plunger 197 which is actuated by a floating lever 198. The right hand end of this lever 198 is attached to a link 199 carried by the clapper or armature 200 of the electromagnetic device 201. The left hand end of the floating lever 198 is carried by a second lever 202, this lever being supported at its left hand end by an adjusting screw 203 which is carried by the lever 204, this lever being pivoted about a knife edge 205 and actuated by a boiler pressure responsive device 206, against the action of a biasing spring 207 which is provided with an adjusting screw 208. The right hand end of the lever 202 is supported by a cam follower 209 which rides a cam 210, this cam being pivoted at 211 and actuated through a lever 212 by the plunger 213 which is mounted upon a diaphragm 214. This diaphragm 214 is housed by a housing or base member 215 which is supported by the pipe 216 attached to the delivery pipe 4. The diaphragm 214 is therefore subjected to the pressure of the gas being delivered to the burner. The gas pressure on the diaphragm 214 is balanced by means of a biasing spring 217 which is attached to a lever 218 rotating the cam 210. This spring 217 is provided with an adjusting screw 219.

The pilot valve mechanism 195 is similar to the corresponding pilot valve mechanisms of Figures 3 and 5 and is provided with an inlet connection to its restrictor member which is connected by pipe 220 to the outlet of the filter 221 which filter is connected by pipe 222 to the off-take pipe 10 of the boiler 1. This filter 221 is provided with a blow-down pipe 223 having a blow-down valve 224, this pipe being connected to the pressure responsive device 206.

The lever 204 in addition to actuating the lever 202 also actuates through an extension 225 the mercury switch carrier 226 which carries the mercury switch 227. This mercury switch 227, the low water cut-off 16, the safety pilot control 17, and the pressure responsive device 132 are wired in series with the electromagnetic device 201, the arrangement being the same as in Figure

1. Thus the electromagnetic device 201 is energized only when all of the operating conditions of the boiler are proper.

Assuming that all of the operating conditions are proper, the electromagnetic device 201 will be energized which causes the right hand pivot point of the floating lever 198 to be raised to normal operating position. Assuming that the boiler pressure increases, the plunger 228 of the pressure responsive device 206 will rotate the lever 204 downwardly about its pivot 205 which will cause lowering of the left hand end of the floating lever 202. This in turn will lower the left hand end of lever 198 which will lower the valve plunger 197 for reducing the pressure applied to the pressure motor. This will permit the weight 189 to operate toggle members 186 and 187 for moving the main valve towards closed position and for urging the diaphragm 184 to the right. This will force condensate from the pressure motor into the float chamber 192. If the water level in the float chamber rises to a point wherein the condensate may be forced into pipe 194, the float valve 193 will open for permitting such excess condensate to escape. As the main valve closes due to the action just described, the discharge pressure of the gas will lower which will permit the spring 217 to rotate the cam 210 counterclockwise against the action of diaphragm 214. This rotation of the cam 210 will raise the right hand end of the lever 202 for thereby shifting the pilot valve plunger 197 to a position for stopping further movement of the main valve. Upon a decrease in boiler pressure the opposite action will occur. Thus at such time the lever 204 will be rotated clockwise for raising the left hand end of lever 202 which in turn causes raising of the valve plunger 197. This will increase the pressure applied to the surface of the condensate in float chamber 192 thus forcing condensate into the pressure motor which will cause the diaphragm 184 to move to the left for increasing the opening of the main valve and the uptake damper a greater extent. As the main valve opens, the discharge pressure will increase which will force the diaphragm 214 upwardly against the action of spring 217, thereby rotating cam 210 clockwise for lowering the right hand end of floating lever 202 which will in turn cause lowering of the pilot valve plunger 197. Thus the main valve will be stopped when the discharge pressure falls sufficiently to return the pilot valve plunger 197 to its neutral position. From the foregoing description it will be apparent that with the arrangement just described, the main valve is positioned to whatever position is necessary to maintain the required discharge pressure and that the discharge pressure is raised upon decrease in boiler pressure and is lowered upon increase in boiler pressure. It should also be apparent that by this arrangement in which the valve position is controlled by gas discharge pressure, the valve will automatically assume whatever position is necessary to maintain this pressure and consequently a constant discharge pressure will be maintained irrespective of variations in gas supply pressure. For example, assuming that the discharge pressure should increase, the diaphragm 214 will raise for rotating cam 210 clockwise which will cause lowering of the valve plunger 197. This in turn will reduce the pressure applied to the pressure motor which will cause the main valve to close an amount sufficient to maintain the discharge pressure substantially constant.

In order to prevent throttling of the gas to a

point which would not provide proper burner operation, a stop screw 230 is provided for limiting the downward movement of the left hand end of floating lever 202. Thus when the boiler pressure rises to a point at which the lever 204 permits the lever 202 to engage stop screw 230 a further increase in boiler pressure will have no effect upon the position of lever 202. At this time the screw 203 will merely disengage lever 202 and the diaphragm 214 acting through the cam 210 will position lever 202 for maintaining the minimum desired discharge pressure.

Whenever the mercury switch 227 opens, or when any switch of controllers 16, 17, or 132 opens, the electromagnetic device 201 will be de-energized which will lower the right hand pivot of floating lever 198 an amount sufficient to insure that plunger 197 is positioned for completely closing the main valve. At this time the lever 204 and cam 210 will be prevented from raising lever 198 an amount sufficient to cause opening of the valve by means of the stop screw 231. This stop screw also serves to limit the closing movement of the pilot valve for preventing excessive pressures from being applied to the pressure motor.

From the foregoing description it will be apparent that the present invention provides an automatic control system for a boiler or other device utilizing a burner and which controls the burner in a positive and safe manner. It will also be apparent that the present invention provides for gradually controlling the supply of fuel to the burner in accordance with the actual load, preventing the supply of fuel from being reduced below an amount sufficient to provide proper burner operation and completely discontinuing the supply of fuel to the burner whenever any operating condition in the system becomes unsafe. While the present invention has been shown and described as applied to control of a gas burner it is equally adaptable to control of other types of burners such for example as oil burners. While only a few forms of the invention have been disclosed it will be apparent that many changes may be made without departing from the scope of the invention. It is therefore desired to be limited only by the scope of the appended claims.

I claim as my invention:

1. In a burner control system, in combination, a fuel burner, a main valve for controlling the flow of fuel to the burner, a pressure motor comprising a chamber having a movable wall for moving said valve in opening direction, biasing means for biasing said main valve towards closed position, a source of actuating fluid for the motor, means including pilot valve means communicating with said source and said pressure motor for varying the pressure applied to said motor, a first controller actuated in accordance with a condition indicative of the required output of the burner for actuating said pilot valve means, minimum flow stop means operating in response to the position of the main valve to limit control of said pilot valve means by said first controller for preventing said first controller from reducing the burner output beyond a predetermined minimum necessary for proper burner operation, and a second controller actuated in response to said condition for reducing the force applied to said pressure motor independently of said first controller for thereby causing complete closing of said main valve in the event that the

value of said condition indicates that the minimum output of said burner is too great.

2. In a burner control system, in combination, a fuel burner, a main valve for controlling the flow of fuel to the burner, a pressure motor comprising a chamber having a movable wall for moving said valve in opening direction, biasing means for biasing said main valve towards closed position, a source of actuating fluid for the motor, means including pilot valve means communicating with said source and said pressure motor for varying the pressure applied to said motor, a first controller for actuating said valve means, condition responsive means responsive to a condition indicative of the required output of the burner for positioning said first controller, follow-up means influenced by the position of said main valve for cooperating with said condition responsive means in positioning said first controller, minimum flow stop means influenced by said follow-up means to limit the control of said pilot valve means by said first controller for preventing said first controller from reducing the burner output beyond a predetermined minimum necessary for proper burner operation, and a second controller for actuating said pilot valve means independently of said first controller, said second controller having two positions, one in which the first controller is placed into control of said pilot valve means and another in which the pilot valve means is positioned independently of said first controller in a manner to completely close said main valve, said last position being assumed whenever the value of said condition indicates that the minimum output of said burner is too great.

3. In a burner control system, in combination, a fuel burner, a main valve for controlling the flow of fuel to the burner, a pressure motor comprising a chamber having a movable wall for moving said valve in opening direction, biasing means for biasing said main valve towards closed position, a source of actuating fluid for the motor, means including pilot valve means communicating with said source and said pressure motor for varying the pressure applied to said motor, a first controller for actuating said valve means, condition responsive means responsive to a condition indicative of the required output of the burner for positioning said first controller, minimum flow stop means for limiting control of said pilot valve means by said first controller for preventing said first controller from reducing the burner output beyond a predetermined minimum, said stop means including a movable member moved into control relationship with said valve means in response to reduction in fuel flow to the predetermined minimum, and a second controller for actuating said pilot valve means independently of said first controller, said second controller having two positions, one in which the first controller is placed into control of said pilot valve means and another in which the pilot valve means is positioned independently of said first controller in a manner to completely close said main valve.

4. In a burner control system, in combination, a fuel burner, a main valve for controlling the flow of fuel to the burner, a pressure motor comprising a chamber having a movable wall for moving said valve in opening direction, biasing means for biasing said main valve towards closed position, a source of actuating fluid for the motor, means including pilot valve means communicating with said source and said pressure motor

for varying the pressure applied to said motor, a controller for actuating said pilot valve means, condition responsive means responsive to a condition indicative of the required output of the burner for positioning said controller, minimum flow stop means for limiting control of said pilot valve means by said controller for preventing said controller from reducing the burner output beyond a predetermined minimum, said stop means including a movable member moved into control relationship with said pilot valve means in response to reduction in fuel flow to the predetermined minimum.

5. In a burner control system, in combination, a burner, a main valve for controlling the flow of fuel to the burner, a pressure motor for positioning said main valve, pilot valve means for controlling the application of pressure to said motor, condition responsive means actuated in accordance with a condition indicative of the required burner output for actuating said pilot valve means, follow-up means influenced by the position of said main valve for cooperating with said condition responsive means in positioning said pilot valve means, minimum flow stop means for limiting control of said pilot valve means by said condition responsive means and follow-up means for preventing movement of said main valve under the control of said pilot valve means to a position reducing burner operation below a predetermined minimum, second pilot valve means associated with said first mentioned pilot valve means and said motor, said second pilot valve means having a first position in which said first pilot valve means is placed in control of said pressure motor and a second position which causes said pressure motor to close said main valve irrespective of said first pilot valve means, and electromagnetic means for moving said second pilot valve means between said first and second positions.

6. In a burner control system, in combination, a burner, a main valve for controlling the flow of fuel to the burner, a pressure motor for positioning said main valve, pilot valve means for controlling the application of pressure to said motor, condition responsive means actuated in accordance with a condition indicative of the required burner operation, a member positioned thereby for actuating said pilot valve means, follow-up means including a device responsive to a condition which is indicative of the flow of fuel to the burner for cooperating with said member in positioning said pilot valve means, and stop means associated with said member for causing said member, operating under the control of said device, to position said pilot valve means for maintaining a predetermined minimum flow of fuel to the burner when the condition responsive means calls for a flow of fuel below said predetermined minimum.

7. In a burner control system, in combination, a burner, a main valve for controlling the flow of fuel to the burner, a pressure motor for positioning said main valve, pilot valve means for controlling the application of pressure to said motor, condition responsive means actuated in accordance with a condition indicative of the required burner operation for actuating said pilot valve means, follow-up means including a device responsive to flow of fuel to the burner for cooperating with said condition responsive means in positioning said pilot valve means, stop means associated with said condition responsive means for causing said flow responsive means to posi-

tion said pilot valve means for maintaining a predetermined minimum flow of fuel to the burner when the condition responsive means calls for a flow of fuel below said predetermined minimum, electromagnetic means for positioning said pilot valve means in a manner to close said main valve irrespective of said stop means, and switching means actuated by said condition responsive means for energizing and deenergizing said electromagnetic means.

8. In a burner control system for a steam boiler, in combination, a burner for said boiler, a main valve for controlling the flow of fuel to the burner, a pressure motor for opening said main valve, biasing means for closing said main valve, connecting means between the boiler steam space and said pressure motor for utilizing steam pressure for actuating said pressure motor, said connecting means including pilot valve means for controlling the magnitude of the steam pressure applied to said pressure motor, a first controller for said pilot valve means, means responsive to the pressure in the boiler for gradually actuating said first controller, minimum flow stop means operated in response to the position of said main valve for preventing said first controller from actuating said pilot valve means in a manner to reduce the flow of fuel below a predetermined minimum necessary for proper burner operation, and a second controller actuated in accordance with boiler pressure for relieving pressure from the pressure motor independently of said first controller for thereby closing completely said main valve whenever the boiler pressure rises above a predetermined value indicating that the minimum fuel flow is too great.

9. In a burner control system for a steam boiler, in combination, a burner for said boiler, a main valve for controlling the flow of fuel to the burner, a pressure motor for opening said main valve, biasing means for closing said main valve, connecting means between the boiler steam space and said pressure motor for utilizing steam pressure for actuating said pressure motor, said connecting means including pilot valve means for controlling the magnitude of the steam pressure applied to said pressure motor, a first controller for said pilot valve means, means responsive to the pressure in the boiler for gradually actuating said first controller, minimum flow stop means for preventing said first controller from actuating said pilot valve means in a manner to reduce

the flow of fuel below a predetermined minimum necessary for proper burner operation, an electro-magnetic device having a first position for rendering said stop means effective to prevent closing of said main valve and a second position for closing said main valve independently of said first controller, and boiler pressure responsive switching means for deenergizing said electro-magnetic device when said boiler pressure rises to a value indicating that the minimum flow of fuel is too great.

10. A control device of the character described comprising in combination, pilot valve means for controlling the operating pressure of a pressure operated fuel valve, means adapted to respond to a condition indicative of the demand for burner operation, a member positioned by said responsive means for operating said pilot valve means, follow up means adapted to be moved as a result of movement of said fuel valve for cooperating with said member in the operation of said pilot valve means, means limiting the operation of said pilot valve means by said member to prevent said member from reducing the flow of fuel below a predetermined rate, and means adapted to respond to a condition indicative of the need for complete termination of burner operation for operating said pilot valve means in a manner to cause closure of said fuel valve independently of said member.

11. A control device of the character described comprising in combination, pilot valve means for controlling the operating pressure of a pressure operated fuel valve, means adapted to respond to a condition indicative of the demand for burner operation, a member positioned by said responsive means for operating said pilot valve means, follow up means adapted to be moved as a result of movement of said fuel valve for cooperating with said member in the operation of said pilot valve means, a device operated by a portion of said follow up means for taking the control of said pilot valve means away from said member when said fuel valve reaches a predetermined minimum open position to prevent said valve from closing further, and means adapted to respond to a condition indicative of the need for complete termination of burner operation for operating said pilot valve means in a manner to cause closure of said fuel valve independently of said member and said device.

JOHN L. HARRIS.
